UNITED STATES PATENT OFFICE.

LEO J. GRUBMAN, OF NEW YORK, N. Y., ASSIGNOR TO VOICES, INCORPORATED, OF NEWARK, NEW JERSEY, A CORPORATION OF DELAWARE.

SOUND-PRODUCING REED.

Application filed November 15, 1923. Serial No. 674,809.

To all whom it may concern:

Be it known that I, LEO J. GRUBMAN, a citizen of the United States, and a resident of the city, county, and State of New York, have invented certain new and useful Improvements in Sound-Producing Reeds, of which the following is a specification.

This invention relates to sound producing reeds and broadly considered, comprehends a reed more particularly designed for use in articulating sound producing devices for toys which is of substantial construction and not likely to get out of order and will also produce sound in constant volume and pitch.

It has heretofore been quite a difficult matter to produce such sounding reeds of standard uniform construction with positive assurance that each reed in the passage of air under pressure therethrough will emit identically the same volume of sound in the same key or pitch. These prior devices usually consisted of a channeled body member having a vibratory metal tongue secured over the open side of the channel. In some cases, the free end of the tongue is curved away from the ingress end of the channel and in others the side walls of the channel at its ingress end are curved to extend in divergent relation to the free end of the tongue. Also the clamping or securing means for the metal tongue to hold the same in a fixed position, in some cases, has a distorting effect upon the tongue.

Where the free end of the tongue is curved, it is not possible to obtain exactly the same degree of curvature in every device and, therefore, the tone pitch of the emitted sound will differ in the different reeds.

The channel members are formed in a die and the opposite edges of the channel after trimming are rough and uneven so that when a straight metal tongue is employed there will be a leakage of air.

Owing to the curvature of the ingress end of the channel, it is not possible to evenly plane down these rough edges and therefore in this case also an improper sound will be produced. Further, in these prior art devices, no provision is made for preventing the angular movement of the vibratory tongue out of parallel relation with the channel member.

It is the object and purpose of my present

improvement to entirely eliminate the above noted deficiencies in sounding reeds as heretofore constructed and to provide means whereby the vibratory metal tongue is held in an absolutely fixed position relative to the channeled body member and without distortion thereof and with the free end of said tongue in every device bearing exactly the same spaced relation to the ingress end of the air channel so that in every device precisely the same degree of vibration will be imparted to the tongue and, therefore, exactly the same volume and tone pitch of sound will be produced.

It is also another object of my invention to provide an improved means for mounting the sounding reed in an opening or passage without employing mechanical fastening elements to positively fix the reed support in place and which will properly retain the reed in applied position without danger of casual displacement, and yet admit of the easy and quick removal of the reed and its support from said opening or passage.

With the above and other objects in view, the invention consists in the improved sounding reed and in the form, construction and relative arrangement of its several parts as will be hereinafter more fully described, illustrated in the accompanying drawings and subsequently incorporated in the subjoined claims.

In the drawings wherein I have illustrated one simple and practical embodiment of the invention and in which similar reference characters designate corresponding parts throughout the several views:

Figure 1 is a side elevation of my improved reed showing the same mounted in its support;

Figure 2 is an edge view thereof;

Figure 3 is a transverse section taken on the line 3-3 of Figure 1;

Figure 4 is a detail elevation of the vibratory metal tongue;

Figure 5 is a view of a tubular sound emission member partly in section showing my improved reed mounted therein;

Figure 6 is a fragmentary sectional view showing the manner of mounting the reed in an air expelling member of a sound producing device;

Figures 7 and 8 are detail views illus-

trating two examples of prior art methods of making such sounding reeds;

Figure 9 is an end elevation showing the old construction illustrated in Figure 7;

5 Figure 10 is a detail transverse section showing the manner in which the vibratory metal tongue of the prior art devices is distorted in the mounting of the reed; and

10 Figure 11 is a detail view illustrating another objectionable feature of the prior art constructions.

In the present disclosure, I have selected for purposes of illustration an embodiment of the sound producing reed which is more 15 particularly designed for use in connection with various devices adapted to be incorporated in the body of a doll or other toy figure for the purpose of emitting a characteristic articulated cry. Among other 20 articles of this character which I have devised and disclosed in various co-pending patent applications, as an example thereof, reference may be had to the application filed by me on December 20th, 1922, Serial No.

25 607,931. However, it will be manifest as this description proceeds that in so far as the novel features of the subject matter of this application are concerned, the sound producing reed of my improved construction is of more or less general application and may be employed in connection with numerous other devices or wind instruments differing widely in structure and the particular purpose for which they may be devised.

30 Referring now more particularly to Figures 1 to 6 inclusive of the drawings, I have illustrated the body of the reed as consisting of an elongated semi-cylindrical member 5. This member is formed from metal or other 40 easily workable material and is of semi-circular cross-sectional shape to provide a longitudinally extending channel 6. The side edges of this channeled body member are 45 outwardly flanged as at 7. The body wall of the member 5 at the ingress end of the channel 6 is rounded or convex as at 8 and the side flanges 7 are integrally connected and extend around this end of the member 5 50 in concentric relation thereto.

Upon the edges of the flanges 7 from the opposite or ingress end of the channel 6 to a point intermediate the ends of the member 5, the longitudinally extending shoulders 9 are formed. From the inner ends of these shoulders to the end 8 of the member 5, the opposite flanged edges of said member at the open side of the channel 6 are obliquely inclined or slightly curved as at 10 thereby gradually decreasing the depth of this portion of the channel 6.

The vibratory sound producing element of the reed consists of a thin flexible metal plate 11 substantially equivalent in length 65 to the length of the member 5 having a rela-

tively wide portion 12 which, as shown in Figure 3 of the drawings, is seated upon the flanges 7 between the shoulders 9 thereof. The remaining portion 13 of said flexible metal plate normally extends in parallel relation with the axis of the channel 6 beyond the inner ends of the shoulders 9 and over the open side of the ingress end of the channel. By reason of the fact that this end of the member 5 at the open side of the channel 70 is obliquely inclined as above described, it will be seen that the same extends in divergent relation to the opposed side of the tongue 13, the ingress opening for the entrance of air to said channel 6 thus gradually increasing in area to the extremity of said tongue.

As shown in Figure 3, the shoulders 9 are of appreciably greater height than the thickness of the metal plate 12, and upon the 85 wider portion of said plate, a strip of fibre, metal or other pressure resisting material 14 is adapted to be arranged between said shoulders.

90 Preferably, as a means of support for the reed, I provide a cylindrical collar or plug 15 of cork or other compressible resilient material. This plug is provided with an appropriately shaped opening therein to receive the assembled parts of the sounding 95 reed, said reed preferably being arranged in the collar or plug with an equal portion thereof projecting from opposite sides of said collar, though this is not essential. If desired, the reed may be positioned in the 100 plug at any point along the length of the shoulders 9.

105 In the use of the compressible or resilient collar or plug 15, the fibre or metal strip 14 subserves a very important purpose. Thus as shown in Figure 5 of the drawings, if the device is to be arranged in a sound emitting tube T, when the collar or plug is forced under pressure into the end of the tube bore, the yieldable cork or other material of which the plug is composed is compressed inwardly upon the sounding reed. The metal plate of which the vibratory sound element is formed being very thin, 110 such compressing pressure thereon would bend or distort the same, tending to force said thin metal plate into the channel of the reed body as indicated at R in Figure 10 of the drawings. However, by interposing the strip or layer of metal or other reinforcing material 14 between the metal plate and the wall of the opening through the collar or plug 15, the plate is relieved of such distorting pressure which will be resisted by 115 the strip of reinforcing material. It is obvious that distortion of this metallic sound producing element to the extent indicated in Figure 10 of the drawings would result in 120 a very marked difference in the kind of sound produced in the vibration of the free

125

130

end portion or tongue of said plate from that which would be obtained if the plate is free from such distorting pressures. Therefore, it will be appreciated that by the use of the reinforcing strip 14, the plate is positively held between the shoulders 9 on the body member. Accordingly, the full force and effect of the air as it is forced under pressure into the ingress end of the channel 6 upon the vibratory tongue 13 of the sounding element is secured and the greatest possible volume of sound may thus be produced from the available air pressure.

15 In the instance shown in Figure 5 of the drawings wherein the plug or support 15 for the sound producing reed is arranged within the tube and adjacent one end thereof, the other end of said tube is closed by means 20 of a plug P. If after testing the device, it should be found that due to some fault in the detail parts of the reed structure, the proper sound is not produced, the device may be readily removed without injury to 25 the parts of the reed by simply removing the plug P and inserting a suitable implement into the tube and exerting a pressure upon the collar 15 thereby forcing said plug with the reed from the open end of the tube. 30 It is possible that this structural fault may be readily corrected, so that the reed may be again inserted within the end of the tube and used.

35 In Figure 6 of the drawings I have shown the improved reed with the resilient or compressible supporting collar therefor mounted in an opening O provided in a movable air expelling head or piston H as employed in certain of the devices shown in my co-pending applications. In this instance, the sound is emitted from the reed into a sound receiving chamber C in said head, the open side of said chamber being closed by a suitable plate having an opening therein in line with the 40 opening O. Thus in this case likewise it will be understood that the plug 15 in which the sounding reed is mounted may be readily removed from the head H when it is necessary to repair the reed or replace the same 45 with a new one.

50 It will be manifest from the foregoing description that by reason of the construction and correlation of the body member 5 and the sounding element 11 of the reed and the means which I employ for supporting and retaining said parts in their proper co-operative positions, perfect uniformity in the production of sound may be obtained so that the quantity production of such devices 55 with the assurance that there will be no appreciable audible distinction between sounds produced by any two of such devices may be realized. This is due to the fact that the sound producing element of the reed is relieved of all distorting pressures and the

60 vibratory tongue 13 thereof is straight or uncurved, while at the same time the proper graduation or increase of space between this vibratory tongue and the open side of the air channel in the reed member 5 is produced 70 by curving or inclining the opposed open side of said channeled body member in divergent relation to the tongue.

65 As shown in Figure 7 of the drawings, it has heretofore been attempted to provide a 75 reed of this character with a straight or uncurved vibrating tongue. In forming the channel member, however, when the side edges thereof are trimmed, upstanding burrs remain thereon as indicated at B so that the 80 tongue A does not properly seat on the edges of said channel member as shown in Figs. 7 and 9 and there is an escape of the air from said channel around the edges of the tongue substantially over the entire 85 length of the latter. Thus in such a construction, proper vibration of the tongue is not obtained and relatively weak and uncertain sound is produced. In my present construction, however, it will be noted that the 90 vibrating tongue 13 is spaced at its marginal edges from the marginal edges of the corresponding end portion of the channeled member 5 so that even though the edges of the 95 latter member may be rough or uneven, there will be no contact of the vibrating tongue therewith. The metal sound producing element is stamped out in predetermined form, and preferably, the vibrating tongue 13 on one 100 end thereof is appreciably narrower than the remaining portion of said element which is seated upon the flanges 7 of the member 5 between the shoulders 9 thereof. Therefore it will be apparent that in every device embodying my improved reed construction the free vibrating tongue of the sound producing element is of exactly the same length, the fulcrum point thereof being substantially at the juncture of the inner end of such relatively narrow tongue with the 105 wider portion 12 of the sounding element.

110 As seen in Figure 8 of the drawings, where the vibratory end of the tongue is curved so as to diverge away from the open side of the channel at its egress end, it has heretofore been the practice to secure said tongue A' over the open side of the channel by closely wrapping a thread D around the channel member and said tongue. However, it has been found that such wrapping is a costly 115 operation with uncertain results. Accordingly, it will be appreciated that the shoulders 9 as provided in my improved construction are quite important and very effective to prevent angular displacement of the metal sounding element so that it is always retained in accurate parallel relation with the axis of the reed member 5. Without the provision of said shoulders, the metallic sounding element both when the wrap- 120

- ping thread D is employed or when the reed is mounted in a compressible collar or plug, is quite likely to gradually assume such an angular position with relation to the body member of the reed as I have indicated in Fig. 11 of the drawings, so that a squeaking sound of small volume would be produced, and in some instances the device might entirely fail to function.
- 10 From the foregoing description considered in connection with the accompanying drawings, it is believed that the several novel structural features of my present improvement as well as the advantages thereof in 15 practical operation will be readily appreciated. Owing to the very simple form of the various elements, a sounding reed of such construction can be produced at comparatively small manufacturing cost. As I 20 dispense with the use of glue, binding thread or similar fastening means, it is also possible to very rapidly assemble the several elements of the reed. I have described and illustrated in the accompanying drawings, a structural embodiment of the device which I have found to give highly satisfactory results in practice. Nevertheless it will be apparent that in adapting my present invention to various uses to which it is applicable, it may be found desirable to resort 30 to certain mechanical changes in the detail structural parts thereof, and I, therefore, reserve the privilege of adopting all such legitimate changes in the form, construction 35 and relative arrangement of the several elements as may be fairly considered within the spirit and scope of the invention as claimed.
- I claim:
1. A reed comprising a body member having a longitudinally extending air channel opening upon one side thereof and provided with angular shoulders at opposite edges of said channel, a vibratory sound producing element having a part positioned over said 40 channel between said shoulders and another relatively yieldable vibrating part projecting longitudinally over the ingress end of the air channel beyond said shoulders, a pressure resisting material engaged upon the first 45 named part of said sound producing element and also positioned between said shoulders, and a support for the reed coacting with said pressure resisting material and holding said material and the sound produc-
- ing element against longitudinal movement 55 with respect to the reed body.
2. A reed comprising a body member having a longitudinally extending air channel opening upon one side thereof and laterally projecting flanges extending along the opposite edges of said channel, said flanges being provided with angular shoulders extending from the egress end of the air channel to points substantially midway of the length of 60 said body member, a vibratory sound producing element overlying said flanges and having a relatively wide part positioned between said shoulders, said element having a relatively narrow vibrating tongue at one end projecting beyond said shoulders over 65 the ingress end of the air channel, a support through which the reed body is positioned, and a member arranged between said shoulders of the reed body upon the wider part 70 of said sound producing element and interposed between said support and said element to prevent distortion of the latter and hold 75 said element against longitudinal shifting movement relative to the reed body.
3. A reed comprising a body member having a longitudinally extending air channel opening upon one side thereof and laterally projecting flanges extending along the opposite edges of said channel, said flanges being provided with angular shoulders extending 80 from the egress end of the air channel to points substantially midway of the length of said body member, a vibratory sound producing element overlying said flanges and having a relatively wide part positioned between said shoulders, said element having a relatively narrow vibrating tongue at one end projecting beyond said shoulders over 85 the ingress end of the air channel, a support of compressible material having an opening 90 therein to receive the reed and adapted to surround the intermediate portion of the reed body, and a non-compressible member also positioned between said shoulders of the reed body upon said sound producing element and receiving the pressure of said support to prevent distortion of the sound producing element and longitudinal shifting 95 movement thereof relative to the body.
- In testimony that I claim the foregoing as my invention, I have signed my name hereunder.

LEO J. GRUBMAN.
